(57) **CLAIM**

The ornamental design for an electrical box, as shown and described.

DESCRIPTION

This application claims the benefit of application Ser. No. 17/723,176 now utility patent US 11,424,604B1- George Emmanuel Mon as sole inventor.

FIG. 1 is a perspective view of the electrical box in accordance with the present invention first embodiment from the front and one longitudinal side, the longitudinal side shown being representative of both longitudinal sides.

FIG. 2 is a perspective view of the electrical box of FIG. 1 from the back and one longitudinal side, the longitudinal side shown being representative of both longitudinal sides. FIG. 3 is a perspective view of the electrical box of FIG. 1 from the front and one transverse side, the transverse side shown being representative of both transverse sides.

FIG. 4 is a perspective view of the electrical box of FIG. 1 from the back and transverse side, the transverse side shown being representative of both transverse sides.

FIG. 5 is an orthographic longitudinal side view of the electrical box of FIG. 1 and defining the section of FIG. 9. FIG. 6 is an orthographic transverse side view of the electrical box of FIG. 1 and defining the section of FIG. 8. FIG. 7 is an orthographic front view of the electrical box of FIG. 1.

FIG. 8 is a perspective longitudinal section of the electrical box of FIG. 1.

FIG. 9 is a perspective transverse section of the electrical box of FIG. 1.

FIG. 10 is a perspective view of the electrical box in accordance with a second embodiment showing the front and one transverse side, the transverse side shown being representative of both transverse sides.

FIG. 11 is a perspective view of the electrical box of the second embodiment of FIG. 10 showing the back and one longitudinal side, the longitudinal side shown being representative of both longitudinal sides; and,

FIG. 12 is a perspective view of the electrical box first embodiment of FIG. 1, claimed portion only, from the front and one longitudinal side.

(Continued)

The broken lines in the Figures are for the purpose of illustrating portions of the electrical box that form no part of the claimed design. Those portions depicted by broken lines are shown as see-through to more clearly depict the claimed design. The electrical box first and second embodiment are not limited to the scale shown herein.

1 Claim, 12 Drawing Sheets
